PUMP OR MOTOR

Walter Ernst, Mount Gilead, Ohio, assignor to
 The Hydraulic Press Corp. Inc., Wilmington,
 Del., a corporation of Delaware

Application January 25, 1938, Serial No. 186,859

2 Claims. (Cl. 103—161)

This invention relates to hydraulic pumps or motors, and in particular, to such pumps or motors of the radial piston type.

One object of this invention is to provide a hydraulic pump or motor having radially reciprocating pistons adapted to engage a three-piece secondary rotor consisting of an annular central portion of a harder material, or with harder surface characteristics, than the side portions to 10 which it is attached and by which it is supported.

Another object is to provide a hydraulic pump or motor, as described above, wherein the central annular portion of the secondary rotor is engaged by rollers supported by needle bearings 15 in the outer ends of pistons reciprocating radially in the radial bores of a cylinder barrel or primary rotor, supported upon a pintle.

Another object is to provide a pump or motor of the above described construction, wherein the side portions of the secondary rotor are rotatably supported on tapered roller bearings, cooperating 20 with the needle bearings of the piston crossheads to counteract the outward thrust tendency imparted to the secondary rotor side members during the operation of the pump or motor.

Another object is to provide a pump or motor of the above described construction, wherein the outer ends of the pistons are provided with squared heads having lubricant passages there- 30 across for the more efficient distribution of lubricant, these squared heads preferably reciprocating in parallel walled guideways in the periphery of the primary rotor or cylinder barrel.

Another object is to provide a pump or motor of the above described construction, wherein the primary rotor is rotatably supported on the pintle by means of tapered roller bearings which cooperate with the tapered roller bearings supporting 35 the secondary rotor in such a manner as to counteract the thrusts exerted thereon during the operation of the pump or motor.

Another object is to provide a pump or motor of the above described construction, wherein opposed tapered roller bearings are employed both for supporting the primary rotor upon the pintle and the secondary rotor upon the secondary rotor support, these oppositely disposed tapered roller bearings cooperating to oppose and counteract the spreading tendency of the secondary rotor 40 portions, thereby equalizing the internal forces and thrusts arising in the operation of the pump or motor, reducing the deflection of the axle supporting the crosshead rollers, and preventing binding both of this axle and of the crosshead 45 rollers.

Another object is to provide a hydraulic pump or motor having a bell-shaped outer casing with flattened bearing portions for slidably supporting the secondary rotor support or shiftrig, and having flat wearing plates of a bearing metal, 5 such as bronze, to support the thrusts and absorb the wear as the secondary rotor support moves to and fro relatively to the casing.

In the drawings:

Figure 1 is a vertical longitudinal section 10 through the hydraulic pump or motor of this invention, taken in the axis of the pintle.

Figure 2 is a vertical cross section through the axes of the radial pistons, taken along the line 2—2 in Figure 1.

Figure 3 is an enlarged detail view, partly in section, showing the construction of the piston and crosshead unit employed in the pump or motor of Figures 1 and 2.

Figure 4 is a vertical section through the piston 20 and crosshead unit of Figure 3, taken along the broken line 4—4 therein.

Figure 5 is a top plan view of the piston employed in the piston and crosshead unit of Figures 3 and 4.

Figure 6 is a side elevation of the piston and crosshead unit of Figure 5, showing the lubricating 25 passages.

Figure 7 is a side elevation at right angles to the side elevation of Figure 6, showing the additional lubricating passages therein.

In general, the pump or motor of this invention consists of a primary rotor, a secondary rotor adapted to rotate upon an axis eccentric to that of the primary rotor, and pistons reciprocable in radial bores in the primary rotor, these pistons having rollers mounted in anti-friction bearings on the ends thereof and adapted to travel in tracks or grooves in the secondary rotor. As the primary and secondary rotors rotate about their respective axes, the rollers on the ends of the pistons travel back and forth in their tracks or grooves in the secondary rotor, and a reciprocation is imparted to the pistons. At the same time the rollers do not need to travel back and forth in the tracks at the full operating speed of the pump, but merely travel fast enough to make up for the change in peripheral velocity as the primary and secondary rotors turn on their respective anti-friction bearings. At the same time the piston executes a swinging movement about the anti-friction bearings supporting its crosshead rollers.

Furthermore, the secondary rotor is arranged in three portions, namely, a central annular por- 50 55

tion and supporting side portions secured thereto, the central annular portion having a hardened surface, or being of harder material than the side portions, so as to resist the wear attendant upon the operation of the pump or motor, as well as to facilitate the machining of the three portions making up the secondary rotor. A still further feature resides in the construction of the piston and crosshead unit, wherein a squared head is provided with lubricant channels arranged to distribute lubricant to the parallel guide surfaces in the periphery of the primary rotor or cylinder barrel. Additionally provided are wear plates arranged between the secondary rotor support or shiftrig and the flattened bearing portions on the upper and lower inner walls of the bell-shaped outer casing.

Referring to the drawings in detail, Figure 1 shows the hydraulic pump or motor of this invention as consisting of a bell-shaped casing 10 having an end plate 12 secured to one end thereof, as by the cap screws 13. The bell-shaped casing 10 is provided with an axial projection 14, having a longitudinal bore 15 provided with transverse bores 16 and 17 for the passage of working fluid. Mounted in the longitudinal bore 15 is a pintle 18 having a threaded portion 19, which is engaged by a nut 20. The nut 20 has an incision 21 formed therein, the parts 22 and 23 of the nut 20, on opposite sides thereof, being engaged by the cap screw 24 passing loosely through the hole 25 in the part 22, and having its threads engaging the threaded hole 26 in the part 23. By this means the nut 20 may be adjusted to the desired point, whereupon the tightening of the cap screw 24 causes the parts 22 and 23 to be forced toward one another against the threads of the threaded portion 19, thereby causing the nut 20 to remain firmly locked in position, without the danger of slippage in either direction.

The purpose of this nut 20 operating upon the threaded portion 19 is for axially or longitudinally adjusting the position of the pintle 18 in order to adjust the clearances of the anti-friction bearings supporting the primary rotor of the pump, as will hereinafter appear. The nut 20 and threaded portions 19 are protected by a cover cap 27 secured to the end of the projecting portion 14 of the end plate 11 by means of the cap screws 28, threaded into the threaded bores 29 thereof.

The pintle 18 is provided with longitudinally disposed pairs of ducts 30 and 31, respectively, 55 one pair of these ducts serving as pressure fluid intake passages and the other pair as fluid discharge passages. The passages 30 and 31 communicate, respectively, with the cut-away portions 32 and 33 in the reduced diameter portion 60 34 of the pintle. Mounted for rotation on the reduced diameter portion 34 of the pintle 18 is a cylinder barrel or primary rotor 35. For this purpose the pintle portion 34 carries the inner races 36 and 37, respectively, for tapered roller bearings 38 and 39, the outer races 40 and 41 of which are seated in the annular recesses 42 and 43 of the primary rotor 35. The outer races 40 are held in position by the retaining ring 44, secured by means of the set screws 45 to the threaded holes 46 of the primary rotor or cylinder barrel 35. The outer race 41 is held in position by the forwardly projecting flange 47 of the enlargement 48 on the inner end of the drive shaft 49, secured thereto by the set screws 50 en-

gaging the threaded holes 51 in the primary rotor 35.

The inner bearing race 37 is engaged by an end plate 52, secured to the inner end of the pintle 18 by means of the cap screws 53 secured within the threaded holes 54, and with a washer or a plurality of shims 55 arranged therebetween. The inner race 36, however, is loosely mounted so as to slide upon the reduced diameter portion 34 of the pintle 18, and between it and the inwardly projecting flange 56 of the end plate 11 is arranged a sliding ring 57. As a consequence, it will be seen that the turning of the nut 20 upon the threaded portion 19 of the pintle 18 will cause the pintle to move axially. Assuming that this motion is to the left (Figure 1), the end plate 52 will force the inner race 37 to engage the rollers 38. These, in turn, engage the outer race 41 and force it and the primary rotor 35 to the left, together with the opposite outer race 40 and its rollers 39. The inner race 36, however, is prevented from moving to the left because of the presence of the sliding ring 57 engaging the flange 56 on the end plate 11, and consequently remains stationary while the pintle portion 34 slides through it. The result is that the diametrical clearances of the anti-friction bearings 38 and 39 are taken up in this manner so that the bearings may be kept at a tight fit without undue binding or looseness.

The primary rotor is provided with a bore 58 which engages the reduced diameter portion 34 of the pintle 18 with very narrow clearances. The load, however, is taken by the tapered roller bearings 38, whose diametrical clearances may be adjusted to amounts less than the clearance between the primary rotor bore 58 and the pintle portion 34. The latter clearance, therefore, serves merely to permit the free rotation of the cylinder barrel 35 upon the pintle portion 34, 40 and yet to prevent excessive leakage therebetween.

The cylinder barrel 35 is provided with a plurality of radially disposed cylinder bores 59 having outlet ports 60 communicating at their inner ends with the cut-away portions 32 and 33 in the pintle 18. The cylinder barrel 35 is also provided with lubrication passages 61 for transmitting lubricant therethrough. A similar lubricant passage 62 is provided in the drive shaft 49, 50 the latter having an enlarged portion 63 adapted to support the inner races 64 of double tapered roller bearings 65, having an outer race 66 supported in an annular recess 67 in a projecting flange 68 in the end plate 12. The inner races 65 are held in position by a locknut 69 having a washer 71, this being threaded upon the threaded portion 72 of the drive shaft 49. An oil retaining ring 76 surrounds the drive shaft 49 in order to prevent leakage along the drive shaft. 60

Mounted for reciprocating in the cylinder bores 59 are pistons 90 having flattened portions 91 upon their outer ends. Passing through the flattened portions 91, transversely of each piston, is a bore 92 within which is mounted an axle 93 65 having reduced diameter portions 94 on its opposite ends. The axle 93 is surrounded by a double row of anti-friction bearings 95, preferably needle bearings. Mounted upon the reduced diameter portions 94 are rollers 96, adapted 70 to engage the secondary rotor in the manner described below. The needle bearings 95 are separated by an annular ridge 97 on the axle 93. The heads of the pistons 90 are likewise flattened, as at 98, for guiding the piston heads in the 75

primary rotor 35, in the manner hereinafter set forth. Lubricant channels 98a and 98b are arranged in a criss-cross manner in the flattened surfaces 91 and 98 (Figures 3 to 7) for distributing lubricant to the various parts.

The crosshead rollers 96 are arranged to engage grooves forming trackways 99 in the secondary rotor side members 100, secured by the set screws 100a to the central annular portion 101 of the secondary rotor, generally designated 102. The central annular portion 101 is provided with an internal surface which is hardened, or of harder material than the side members 100 so as to withstand the thrust of the crosshead rollers, hereinafter described in detail. By this construction the three-piece secondary rotor is given the effect of a single integral secondary rotor, yet the hardened central portion 101 may be machined and hardened independently of the side portions 100. This construction likewise facilitates the assembling of the secondary rotor and enables the use of cheaper materials in the side portions 100, or of a material in the central annular portion 101 better adapted to give bearing support to the crosshead rollers than the material used for the side portions 100. In addition to this, the central annular portion 101 may, if desired, be made of a special bearing material, such as bronze, for additionally reducing the friction arising in the operation of the pump or motor.

The side portions 100 of the secondary rotor 102 are provided with annular shoulders 103, adapted to support the inner races 104 of anti-friction tapered roller bearings 105. These inner races 104 are held in position by the retaining rings 107, secured by the set screws 108 to the side portions 100 of the secondary rotor. The tapered roller bearings 105 are supported by outer races 106, held in position by the retaining rings 109, secured to the secondary rotor support or shiftring 110. The latter is provided horizontally with diametrically opposed threaded holes 111, within which are mounted the threaded ends 112 of the shift rods 113 (Figure 2).

The shiftring 110 is provided vertically with wear plates 114 with flattened surfaces 115 arranged in recesses 116 within the diametrically opposed flattened portions 117 thereof. The flattened surfaces 115 of the wear plates 114 are arranged to engage the correspondingly flattened projections 118 on the interior walls of the pump casing 10. The shift rods 113 pass outwardly through the casing 10 by way of the bores 119. In this manner the shiftring 110 may be moved to and fro, and slidingly supported upon the flattened projections 118 so as to enable it to be placed in an eccentric position relatively to the axis of the pintle 18 and cylinder barrel or primary rotor 35. When the shiftring 110 is so placed the secondary rotor 100 revolves about an axis which is eccentric to that of the primary rotor 35 so that the pistons 90 are caused to reciprocate radially within their cylinder bores 59 by the engagement of their crosshead rollers 96 with the grooves or trackways 99 in the secondary rotor halves 100. At the same time fluid is supplied and removed from the pump by the pintle passages 30 and 31, communicating with the cylinder bores 59 by way of the ports 68 and cut-away portions 32 and 33. Ports 120 are provided at the top and bottom of the shiftring 110,

thereby exposing the flattened projections 117 to the action of the oil employed as fluid for the pump.

The primary rotor 35 is provided with a ridge 123 having recesses 124 immediately adjacent the tops of the cylinder bores 59, and adapted to engage the flattened surfaces 98 of the pistons 90. In this manner the pistons 90 are provided with additional support during their reciprocation, lubricant being conducted to the opposing surfaces through the lubricating passages 98a.

The operation of the pump or motor of this invention is self-evident from the foregoing description. It will be seen, however, that the opposing tapered roller bearings 38 and 105 cooperate to support the primary and secondary rotors 35 and 102 in such a manner as to prevent the distortion thereof by the thrusts arising during operation. In operation the thrusts of the pistons and their crossheads tend to cause the secondary rotor side members 100 to spread apart, but this spreading tendency is opposed and counteracted by the tapered roller bearings 105. It will be observed that the axes of these tapered roller bearings 105 intersect at the plane 25 passing through the axes of the pistons 90 and cylinder bores 59.

Mounted on the drive shaft 49 (Figure 1) is a pumping gear 140 arranged between the plates 141 and 142 and meshing with a pumping gear 143 supported by anti-friction bearings 144 upon an axle 145. The axle 145 is mounted in sockets 146 and 147 in the plates 141 and 142, respectively. The plates 141 and 142 are separated by an annular member 148, these three members 35 forming a casing for the pumping gears 140 and 143 and inclosing a chamber 149. Access to the chamber 149 is obtained by an aperture 150, closed by a plate 151, secured to the plate 142 by the cap screws 152. The pumping gears 140 and 143 together form a gear pump which is useful in connection with certain hydraulic machinery which the pump is adapted to operate, such as providing an auxiliary leakage pumping system for returning to the surge tank the fluid escaping past the main ram of a hydraulic press.

It will be understood that I desire to comprehend within my invention such modifications as come within the scope of the claims and the invention.

Having thus fully described my invention, what I claim as new and desire to secure by Letters Patent, is:

1. In combination in a hydraulic pump or motor, a primary rotor with cylinders, pistons reciprocable in said cylinders, a three-part secondary rotor having side parts and a central annular part, rollers on said pistons engaging said central part, a supporting member, and tapered roller bearings arranged between said supporting member and the side parts of said secondary rotor.

2. In combination in a hydraulic pump or motor, a primary rotor with cylinders, pistons reciprocable in said cylinders, a three-part secondary rotor having side parts and a central annular part, rollers on said pistons engaging said central part, a supporting member, said side parts having axially extended portions, and tapered roller bearings arranged between said extended portions and said supporting member.

WALTER ERNST.
